ERIC R. CLASSON, OF FLUSHING, NEW YORK

WEATHER STRIP

Application filed October 28, 1930. Serial No. 491,662.

This invention relates to weather stripping for windows and other closures.

One object of the invention is to provide a device of the character described having guides and fastening means in improved interengagement and association to produce a simple, compact, device which is inexpensive to manufacture, easy to install, and which assures sufficient clearance and yet weathertight operation for standard or conventional window sashes and frames.

Another object is to provide a device of the nature set forth having improved means for securing a resilient weather proofing element with a guide means.

Another object of the invention is to furnish an improved offset guide which provides clearance for the fastening means as a result of the offset, regardless whether such offset be in an element secured to the window casing or in one secured to the sash.

Another object is to construct a device of the type mentioned having a channel provided with an improved integral flange guide disposed along the sides of the channel in inward extending relation.

Another object is to furnish a weather stripping having few and simple parts and which is rugged, reliable, and efficient in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawing, wherein like parts are designated by the same reference characters throughout the several views.

In the drawing:

Figure 1 is a view in vertical section of a device embodying the invention showing a typical application thereof.

Fig. 2 is a similar view showing a modification thereof with a spacing element on the window sash.

Fig. 3 is an end view of a modification showing a differently arranged resilient element.

Fig. 4 is an end view of a modification with

the resilient flange arranged entirely beside the fastening flange.

Fig. 5 is an end view of a modification with integral side flanges.

Fig. 6 is an end view of a channel consisting of a plurality of angle members, with a part in section.

Fig. 7 is an end view of a modification made of a one-piece member.

The advantages of the invention as here outlined are best realized when all of its features and instrumentalities are combined in one and the same structure, but, useful devices may be produced embodying less than the whole.

It will be obvious to those skilled in the art to which this invention appertains, that the same may be incorporated in several different constructions. The accompanying drawing, therefore, is submitted merely as showing the preferred exemplification of the invention.

Generally described, this invention provides a weather strip device for windows, and the like, and which can be adapted for different sash and sash casing constructions of whatever size, design, or nature of interengagement. For purposes of illustration, the sash is shown as provided with a recess forming a marginal guide flange or tenon which is thus sufficiently small to be slideable in a suitable compact channel structure to afford a weather tight joint. If desired, the said tenon may have a metal or other friction reducing surface to uniformly contact the metallic channel structure with a minimum wear. The channel structure may include a laterally extending flange for securing the same to sash casing in a convenient manner. A portion of the channel having edgewise abutment with the slide tenon may be offset toward the same to uniformly contact the same and also to provide clearance for the heads of fasteners securing the laterally extending flange to the sash frame.

A resilient element may, if desired, be affixed to a part of the channel structure, and specifically to the laterally extending flange if the latter be made as a fold of metal. Instead of providing an offset in the channel

structure, the slide tenon may be made correspondingly greater, as by causing the metallic facing thereof to extend therebeyond, by offsetting said metallic facing or in other suitable manner. The guide channel structure may also be made an integral inturned flange; it may also be internally fastened to the sash casing. These flanges must be accurately constructed and alined to obtain proper weatherproofing.

Referring in detail to the drawing, 10 denotes a device embodying the invention. The same includes a member such as a sash 11 slidably mounted for movement in any suitable casing 12. To render the sash weathertight, a guide means 13 is arranged on the casing, for engaging the sash while permitting the requisite sliding movement thereof. One type of sash with which the 20 guide means may coat, may have a recess 14 providing a guide flange 15 in the nature of a tenon which is slidable within the guide means. In sashes of this type, the edge 16 of said guide flange lies in the plane of the 25 edge 17 of the sash. Within the principle of the invention, the guide means may be modified in size, proportion, and construction to suit other kinds of sashes.

The said guide means may include a channel 18, or the equivalent. The said channel has a web 19 and a pair of side flanges 20, 21. Connected to the channel, preferably integrally therewith, is an external laterally extending flange 22. One way of constructing this flange 22 is by suitable bends or folds: for instance, folds 23, 24 provided by reverse parallel bends 25, 26 extending along the channel. The flange 22 affords a combined re-enforcement and anchorage for the channel, and may secure the same to the sash casing by any suitable fasteners such as flat headed nails 27, or the like. In the mounted position flange 21 is positioned in the recess 14 and flange 20 in a rabbet 28, both of these 40 flanges preferably coacting with the opposite sides of the sash guide portion 15. Where the sash is made of wood, the guide portion 15 may have a metal facing 29 which may be of channel form and secured to the 45 guide portion in any suitable manner. Preferably the edge of the latter, or of metal facing 29, as the case may be, slidably abuts the web 19 of the guide channel 18. In order to afford a sufficient and positive clearance for the double fold flange 24, or the fasteners 27 thereof, the channel guide may be offset at 50 30 toward the adjacent edge of the sash, and away from or into spaced relation with the sash casing.

The guide construction 13 may be made of any suitable material, whether phosphor bronze, or a rustless steel, or other alloy, and may be rigid or resilient in any desired degree. Accuracy in alinement of parts may

be relied on to assure weather tightness, but if desired, a strip 31 of a higher resilience and of angle shape may be secured, for example with a flange 32 thereof between the folds of flange 22, which may or may not 70 be clamped therein as required. The angle member may be re-enforced and supported by the rigid flange 21 to snugly contact a side of the metal facing of the guide 15.

Fig. 2 shows a modification of the invention which is generally similar to the foregoing except that the offset 30 is omitted, and in place thereof, a spacing means may be provided on the sash, such as offsets 32 in the metallic channel facing 29a. Screws 80 33 countersunk into the flange 22a, may be used to secure the guide channel 18a to the sash casing.

In Fig. 3 is shown a further modification in which the guide channel 18a has a different resilient member 31a, having a flange 34 extending along the length of the web of the guide channel, and a second weather proofing flange 35 remote from the fastening flange 22a. Thus the flange 35 may be positioned on the outer side of the sash.

In Fig. 4 is shown a modification including a one-piece channel 36 having a web 36a and side flanges 37, 38, one of which has an inwardly bent portion 39 for engaging a 95 flange 40 of a resilient strip 41 adjacent to the securing portion and re-enforced thereby.

In Fig. 5 is shown a modification including a one-piece channel 36b wherein the flange 37a also has an inwardly bent portion 42 extending into proximity to the web thereof. The flanges 37a, 38, 39 may be parallel, while the flange 41 of the resilient member may be inclined at a suitable small angle for the resilient sliding contact. The portion 42 adds re-enforcement to the flange 37a and also furnishes additional resilience particularly adjacent to the web, thus allowing for any irregularities in the sash construction.

In Fig. 6 is shown a modification including a pair of angle members 43, 44 which are built up to form a guide channel 45. Flanges 46, 47 of the angle members overlie one another, while the other flanges 48 have inwardly bent parallel guide portions 49 spaced slightly from their corresponding flanges. The guide flanges 49 may extend into proximity to the flanges 46, 47, which may be considered as the web of the channel, to afford a maximum sliding contact. Alined holes 50, 51 may be formed in the flanges 46, 47, and the former may have a rim portion 52 about its hole struck inward 120 to engage in the corresponding hole 51 for interconnecting the angle members 44, 45, if desired.

In Fig. 7 is shown a modification wherein the channel 45a is of one-piece construction,

having a web 53, and side flanges 54, both of which have inward extending parallel portions 55. The web 53 may have countersunk holes 56 for any suitable fasteners.

5 The modifications shown in Figs. 6 and 7 may be rigid, although they preferably possess a degree of resilience. The flanges 48 and 54 have the maximum resilience remote from the web, and the portions or flanges 49 and 55 have the maximum resilience adjacent to the web. Thus the channels are uniformly resilient throughout. The requisite resilience may be obtained by the use of a sufficiently elastic metal, or one of sufficient 15 thinness, or both.

The various forms of the invention may be made by stamping, drawing, or in any other suitable manner.

Resilience or elasticity may be supplied by 20 the employment of fabric or composition materials, for instance, in place of the resilient member 31.

The metal channel facing 29a may be used with any of the modifications shown in Figs. 25 3 to 7, but the facing 29 may be used in Figs. 4 to 7, especially where the fastener heads are fully countersunk.

It will be appreciated that various changes 30 and modifications may be made in the device as shown in the drawing, and that the same is submitted in an illustrative and not in a limiting sense, the scope of the invention being defined in the following claims.

I claim:

35 1. A device including a channel means having a channel proper for slidably guiding and weather proofing a sash, and a laterally extending flange lying in a plane parallel to the plane of the channel web and offset away from the channel flanges, said laterally extending flange providing a means for securing the channel means to a casing for the sash, said flange consisting of an integral flattened fold connecting with the web and a flange of the channel, and a resilient element within the channel and secured in the fold of said flange.

40 2. A device including a channel means having a channel proper for slidably guiding and weatherproofing a sash, and a laterally extending flange lying in a plane substantially parallel to the plane of the channel web and offset away from the channel flanges, said laterally extending flange providing a means for securing the channel means to a casing for the sash, said laterally extending flange consisting of an integral flattened fold connecting with the web and a flange of the channel, said web having an offset adjacent to the laterally extending flange and upward of the same, and a resilient element within the channel and secured in the fold of said flange, in proximity to said web offset.

45 3. A device including a channel means of

relatively rigid sheet metal and having a channel proper for slidably guiding and weatherproofing a window or the like, and a laterally extending flange being disposed in substantially parallel relation to the channel web and offset away from the channel flanges, said laterally extending flange consisting of a fold integral with the channel means, and a resilient element within the channel secured in said fold and extending along the inside face of a flange of the channel means.

4. A device including a channel means of relatively rigid sheet metal and having a channel proper for slidably guiding and weatherproofing a window or the like, said channel means having a recessed portion opening into the channel proper in proximity to the web of the channel means, and a resilient metal member having a plurality of arms interconnected by a fold, one of said arms being secured within said recessed portion, the fold of said member being in proximity to the said web and in contact with a flange of the channel, and the other arm of said member extending in the general direction of said flanges along one of said flanges and having a portion thereof at the end of said arm movably inwardly spaced from the flange along which said other arm extends.

5. A device including a channel means of relatively rigid sheet metal and having a channel proper for slidably guiding and weatherproofing a window or the like, said channel means having a recessed portion opening into the channel proper in proximity to the web of the channel means, and a resilient member having a plurality of arms interconnected by a fold, one of said arms being secured within said recessed portion, the fold of said member being in abutment with said web and a flange of the channel adjacent to said recessed portion, and the other arm of said member extending in the general direction of said flanges along one of them and having a portion thereof movably inwardly spaced from the flange along which said other arm extends.

In testimony whereof I affix my signature.

ERIC R. CLASSON.
